Alfred P. Buisson Jr.

Attorney

UNITED STATES PATENT OFFICE.

LOUIS P. BUISSON, OF NEW YORK, N. Y.

CUFF BUTTON.

Application filed September 6, 1923. Serial No. 661,199.

To all whom it may concern:

Be it known that I, Louis P. Buisson, a citizen of the United States, residing at New York city, in the county of New York and State of New York, have invented certain new and useful Improvements in Cuff Buttons: and I do hereby declare the following to be a full, clear, and exact description of the invention, such as will enable others skilled in the art to which it app pertains to make and use the same.

The invention has for its object the provision of a fastener for cuffs and wristbands of shirt sleeves, which will operate to hold the sleeve at any adjusted position along the arm of the wearer without necessitating the removal of the fastener, or the rolling of the shirt sleeve, or the use of sleeve holding means such as generally employed for securing the sleeve when drawn back upon the arm.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application:

Figure 1 is a side view of a cuff button embodying the invention,

Figure 2 is a sectional view thereof,

Figure 3 is a view similar to Figure 1 of a modification,

Figure 4 is a sectional view of the modification, and

Figure 5 is a detail view showing the application of the invention, the dotted lines indicating different adjusted positions of the sleeve when drawn back upon the arm.

Corresponding and like parts are referred to in the following description and designated in the several views of the drawings by like reference characters.

The cuff button comprises pairs of elements yieldably connected either by means

of a metal spring 1, as indicated in Figures 1 and 2, or an elastic, as shown in Figures 3 and 4. Each pair of elements comprises a front 3 and a back 4, which are connected by means of links 5. The yieldable connection 1, or 2, is attached at its ends to the backs 4 of the pairs of elements and, as indicated in Figure 2, the ends of the spring 1 engage countersunk eyes 6 in the outer faces of the backs 4. In the arrangement shown in Figures 3 and 4, a clip 7 is provided upon the outer face of each of the backs 4 and this clip is in the nature of a socket which receives the end of the elastic 2. The edge of the socket clip is toothed or serrated and the points of the teeth when bent inwardly bite into the elastic 2 and insure a firm connection. However, it is to be understood that the elastic connection may be of any form and secured to the elements 4 in any preferred and substantial way.

The cuff button is of the link type, the yieldable connection serving to admit of the elements engaged with the cuff or wristband of a shirt sleeve being spread and exerting a drawing force to cause the cuff or wristband to bindingly engage the arm and hold the shirt sleeve in the required adjusted position, as indicated by the dotted lines in Figure 5, without requiring the removal of the fastener and the rolling back of the shirt sleeve, or the employment of an elastic band or other type of sleeve holder generally resorted to for securing the shirt sleeve when drawn back upon the arm.

What is claimed is:

A cuff button device having two buttons, each button consisting of a front and a back flexibly connected together, attaching means on said backs, and a resilient means engaged at opposite ends by said attaching means independently of their flexible connection to enable movement of one button as a whole relatively to the other button.

In testimony whereof I affix my signature in presence of two witnesses.

LOUIS P. BUISSON.

Witnesses:

ANNA H. CRETTON,
BERNARD F. MCANDLE.
